UNITED STATES PATENT OFFICE.

GUSTAV A. BARTH, OF ST. LOUIS, MISSOURI, ASSIGNOR TO PIERRE CHOUTEAU, OF SAME PLACE.

STEAM-ACTUATED VALVE.

SPECIFICATION forming part of Letters Patent No. 398,930, dated March 5, 1889.

Application filed November 19, 1888. Serial No. 291,264. (No model.)

To all whom it may concern:

Be it known that I, GUSTAV A. BARTH, a citizen of the United States, residing at the city of St. Louis, State of Missouri, have invented a certain new and useful Improvement 5 in Steam-Actuated Valves for Engines, of which the following is a full, clear, and exact description.

My invention relates to improvements in 10 steam and other motive power engines wherein in the piston is reciprocated in the cylinder by the action of its valve without the intervention of valve-operating mechanism, and has for its object to obtain a uniform pressure 15 on both sides of the piston and to simplify the arrangement of the parts.

My invention comprises a cylinder having combined inlet and exhaust ports and passages to and from a steam-chest containing a 20 slide or distribution valve and provided with inlet and exhaust ports, a piston fitted within the cylinder and having a rod working through a tubular projection on the cylinder-cover, separate relief-passages opening from the 25 tubular projection into the steam-chest behind the ends of the distribution-valve, with corresponding passages in the piston-rod opening, respectively, from each side of the piston, the whole operating to hold and reverse 30 the distribution-valve at the proper times and thereby control the admission and exhaust of steam or other motive fluid to and from each side of the piston alternately.

On the accompanying drawings, Figure 1 35 represents a central longitudinal section of my improved steam or other motive-power engine, the piston being shown at the rear end of its stroke in the cylinder; Fig. 2, a similar view thereof with the piston at the 40 front end of its stroke; Fig. 3, a longitudinal section on line 1 1 in Fig. 2, and Figs. 4 and 5 transverse sections on lines 2 2 and 3 3, respectively, in Fig. 1. Figs. 6 and 7 are similar views to Figs. 1 and 2, respectively, of my 45 invention as applied to a direct-acting steam or pneumatic engine used for mining purposes; Fig. 8, a longitudinal section thereof on line 4 4 in Fig. 6; Fig. 9, a transverse section thereof on line 5 5 in Fig. 6, with the cylinder-cover removed; and Figs. 10 and 11, 50 transverse sections on lines 6 6 and 7 7, re-

spectively, in Fig. 6, like letters of reference denoting like parts in the respective figures.

Referring to Figs. 1 to 5, *a* represents a cylinder having combined inlet and exhaust ports and passages *b b'*, opening, respectively, from the rear and front end of the cylinder *a* into a steam-chest, *c*, which is provided with an inlet-port, *d*, and exhaust-ports *e e'*.

Within the steam-chest *c* is fitted a slide or 60 distribution valve, *f*, preferably circular in form, and having three circumferential grooves or passages, *g g' g²*, which extend entirely around the valve *f*, the passage *g* commanding the inlet ports and passages *d b* and *d b'* alternately, passage *g'* commanding the outlet passage and port *b e* and the passage *g²* commanding the outlet passage and port *b' e'* during the operation of the valve *f*, as hereinafter more particularly described. 70

h represents the piston fitted within the cylinder *a* and having a rod, *i*, which passes steam-tight through a tube, *j*, projecting from the cover at one end of the cylinder *a* and provided at its outer end with a stuffing-box, *j'*. 75

From the interior of the tube *j*, near the stuffing-box *j'*, a passage, *k*, extends through the wall of the tube *j* and that of the cylinder *a* to the rear end of the steam-chest *c*, into which it opens behind the distribution-valve *f*, a similar passage, *l*, opening from the cylinder end of the tube *j* into the steam-chest *c* behind the opposite or front end of the distribution-valve *f*.

Formed longitudinally through the piston-rod *i* is a passage, *k'*, which opens from the cylinder *a* at the rear side of its piston *h* into the tube *j* for communicating with the relief-passage *k*, and in the circumference of the piston-rod *i*, at the front side of the piston *h*, *g* is a groove or passage, *l'*, for communicating with the relief-passage *l*, as hereinafter more particularly referred to. 85

As seen in Fig. 1, the piston *h* is at the rear end of its stroke in the cylinder *a*, and the slide or distribution valve *f* at the corresponding end of the steam-chest *c*, so that its passages *g g²* establish communication between the inlet-port *d* and passage *b* and between the outlet-passage *b'* and port *e'*, whereby steam or other motive fluid passes from the inlet-port *d* through the passage *b* into the cylinder 95 or from the outlet-passage *b'* through the passage *b* into the cylinder 100.

a on the rear side of the piston *h*, which is thereby forced to the front end of the cylinder *a* until the opening of the relief-passage *k'* in the piston-rod *i* farthest from the piston *h* comes opposite to the opening of the passage *k* in the tube *j*, (see Figs. 2 and 3,) and so allows the steam from the rear side of the piston *h* to pass into the steam-chest *c* behind the rear end of the distribution-valve *f*, which is thereby thrown over or reversed in the steam-chest *c*, so that its passage *g* opens communication between the inlet-port *d* and passage *b'*, and its passage *g'* opens communication between the outlet-passage *b* and port *e*, when steam entering the cylinder *a* on the front side of the piston *h* and exhausting from its rear side will force the piston *h* toward the rear end of the cylinder *a* until approaching the termination of its stroke, when the groove *l'* emerges from the tube *j* into the cylinder *a* and allows the steam to pass from the latter (see Figs. 1 and 4) through the relief-passage *l* into the steam-chest *c* at the front end of the distribution-valve *f*, which is thereby forced to the rear end of the steam-chest *c*, as seen in Fig. 1, and the operation repeated.

In the application of my invention to a direct-acting mining-engine, as shown in Figs. 3 to 11, the relief-passage *k'* is formed through the piston-rod *i'*, which reciprocates within the tube *j*, and is reduced in diameter where it passes through the stuffing-box *j*, so as to form a shoulder thereat for cushioning the piston *h*.

To shorten the stroke of the piston *h*, I may form in the circumference of the piston-rod *i'* a second (or more) groove, *l'*, which is located at a suitable distance rearward from the groove *l'*, for establishing communication between the cylinder *a* on the front side of the piston *h* and the steam-chest *c* at the front end of the distribution-valve *f* at an earlier period of the rear stroke of the piston *h* than occurs with the groove *l'*, the groove *l'* opening into an independent branch of the relief-pas-

sage *l*, so that it may be closed by a cock or valve, *m*, when it is desired that the groove *l'* alone shall make communication with the steam-chest *c* for obtaining the full stroke of the piston *h*.

I claim—

1. The combination of a cylinder, *a*, having combined inlet and exhaust ports and passages *b b'*, a steam-chest, *c*, having inlet-port *d* and exhaust-ports *e e'*, a slide or distribution valve, *f*, located in steam-chest *c*, and formed with circumferential depressions or passages *g g' g²*, a piston, *h*, fitted within the cylinder *a*, and provided with a rod, *i*, passing through a tube, *j*, relief-passages *k* and *l*, opening from the tube *j* into the steam-chest *c* behind the respective ends of the distribution-valve *f*, with corresponding passage *k'* and groove *l'* formed in the piston-rod *i*, substantially as shown, and for the purpose described.

2. In a direct-acting steam or other motive power engine, the combination of a cylinder, *a*, having combined inlet and exhaust ports and passages *b b'*, a steam-chest, *c*, having inlet-port *d* and exhaust-ports *e e'*, a slide or distribution valve, *f*, located within steam-chest *c*, and formed with circumferential depressions or passages *g g' g²*, a piston, *h*, fitted within the cylinder *a*, and provided with a rod, *i'*, passing through a tube, *j*, relief-passages *k* and *l*, opening from the tube *j* into the steam-chest *c* behind the respective ends of the distribution-valve *f*, said passages *l* having a cock or valve, *m*, with a corresponding passage, *k'*, and grooves *l' l²* formed in the piston-rod *i'*, substantially as shown, and for the purpose described.

In testimony whereof I affix my signature, in presence of two witnesses, this 15th day of November, 1888.

GUSTAV A. BARTH.

Witnesses:

S. L. SCHRADER,
PAUL BAKEWELL.
